UNITED STATES PATENT OFFICE.

CHARLES HENRY ATKINS, OF SPRINGFIELD, MASSACHUSETTS.

HOLLOW-BOLT CONSTRUCTION.

1,216,395.

Specification of Letters Patent. Patented Feb. 20, 1917.

Application filed April 22, 1916. Serial No. 93,035.

To all whom it may concern:

Be it known that I, CHARLES HENRY ATKINS, a citizen of the United States of America, residing in the city of Springfield, county of Hampden, and State of Massachusetts, have invented a new and useful Improvement in Hollow-Bolt Constructions, of which the following is a specification.

This invention relates to improvements in 10 drying machines, either for cloth, paper or the like. In drying machines it is important that the bearings and packings are kept steam and water tight, not only to increase the production and output but also to lessen 15 the cost of repairs and increase the efficiency of the plant as a whole.

The present invention relates to improvements for carrying off the water of condensation from the interior of a drying cylinder 20 by means of a discharge pipe which extends into the cylinder and having its open inner end terminating near the lower side of the cylinder, the outlet end of the pipe passing through a hollow bearing box by means of 25 which construction the drying medium, as steam, can enter the cylinder; means is also provided to permit the ready withdrawal of the pipe from the drying cylinder. A hollow bolt surrounds the pipe to provide 30 a means for forming a water and steam tight packing or joint between the box and its bearing. My present invention, in brief, therefore, is confined to devices and means for making a steam and water tight joint 35 between the cylinder shaft and bearing, and, to permit the easy removal of the discharge pipe from the cylinder when required.

The present invention is designed to be used with the steam trap which is shown, 40 described and claimed in my copending application filed of even date herewith for an improvement in steam traps under Ser. No. 93,034.

Referring to the drawings which form a 45 part of the present invention:

Figure 1 is a vertical sectional view of my improvement which is associated with the hollow bearing for introducing steam into the heating drum, the hollow bolt construction, and the spider or packing ring for forcing the joint packing material in place;

Fig. 2 is a detail view of a portion of the bearing box broken away and showing the discharge pipe passing through the bearing 55 into the drying cylinder, the spider or ring for forcing the packing into place about the

shaft which supports and drives the drying cylinder.

Referring to the drawings in detail 1 designates the drying drum which is suitably supported by means of the hollow shaft 2 that is driven in any suitable manner by means of the spur gear 3. The hollow bearing box 4, into which steam is introduced, as indicated by the arrows 5 and 6, allows steam under pressure to flow into the cylinder 1 through the hollow shaft 2. Extending through the shaft 2 and into the drying cylinder 1 is a discharge pipe 7, the inner end of which terminates near the lower side of the cylinder 1. Its outlet end passes through the shaft 2 and the hollow bolt 8 and the hub of the spider 9. This pipe serves the purpose of permitting the confined air in the cylinder 1 to be driven out by the incoming steam. 10 designates a cap that is connected to the bearing 4 by means of the threads 11. The hollow bolt 8 passes through this cap and is connected thereto by means of the threads 12. 13 is a nut that is formed integral with the bolt 8 and by means of which the bolt may be rotated in the cap 10 by any suitable means, as a wrench. The inner end of this bolt engages the hub portion 14 of the spider 9. The arms of the spider are connected to a ring 15 which in turn enters the annular opening 17 between the shaft 2 and the packing box 4 for the purpose of forcing the packing material tightly against the shaft 2 to prevent leakage of steam or water. In order to prevent the escape of steam or water along the pipe 7, the stuffing box 18 is threaded on to the outer end of the hollow bolt 8 and suitable packing material 19, is placed therein. The incoming steam enters the drying cylinder 1 through the hollow bearing 4 and passes as indicated by the arrow 6 through the arms 9 of the spider through the passageway 20 into the cylinder 1. The air is driven out of the cylinder by means of this incoming steam pressure and escapes through the pipe 7, as indicated by the arrows 21 to a suitable trap, or other device.

It will be seen that when the hollow bolt 8 is rotated in the cap 10 the ring 15 is moved inward into the annular opening 17 to compress the packing material therein.

In order to remove the pipe 7 and the spider and packing ring 15 from the cylinder 1 and the hollow bearing box 4 it is only

necessary to unscrew the cap 10, when both can be withdrawn.

From this construction it will be seen that I have provided a simple and inexpensive device for holding the discharge pipe 7 in place and for forcing the packing material into the joint between the hollow supporting shaft 2 and the box 4, and, also to permit the ready removal of the discharge pipe 7 when desired.

What I claim is:

1. In a device of the kind described, a bearing box, a hollow shaft therein for supporting a drying cylinder, a pipe of less diameter than the interior diameter of said shaft and extending through the bearing box into the drying cylinder, a cap having a threaded connection with the bearing box and a threaded opening in the cap, said hollow bolt engaging the threaded opening of the cap and through which bolt the outer end of the steam outlet pipe passes, a spider, a packing ring connected thereto and located at the inner end of the hollow bolt and through which the steam outlet pipe passes, said bolt serving the purpose for engaging the spider and for forcing the packing ring against packing material as the said bolt is screwed into the cap and against the spider of said ring, said material being located in an annular packing receiving chamber between the hollow shaft and the bearing box, whereby when the hollow bolt is rotated in the concentric opening the packing material may be forced inward by the packing ring.
2. In a device of the kind described, the combination with a drying cylinder, a discharge pipe extending into and near the lower side of the cylinder, a hollow bearing box, a hollow shaft for supporting said cylinder and through which the pipe passes to provide an annular space around said pipe to permit the entrance of a heating medium, as steam, a hollow bolt having threads on its external surface, for engaging a threaded opening in the hollow bearing box, a packing ring adapted to be engaged by said bolt for forcing the ring inward and a stuffing box on the end of the hollow bolt to prevent the escape of steam from the bearing box.

3. A device of the kind described comprising, in combination, a bearing box having an annular space to contain packing material, a hollow externally threaded bolt secured to the box by means of threads in a cap on the

box, a steam pipe passing through the bolt, a stuffing box on the end of the bolt, a packing ring on the pipe comprising a ring portion, a hub, an arm connecting the hub and ring portion and adapted to be engaged by the inner end of the bolt for forcing said ring portion inward toward the box as the bolt is rotated in said cap for the purpose of moving the packing material into said annular space between the shaft in the box and said box, as described.

4. The combination in a structure of the kind described with a hollow bearing box for admitting a heating medium thereto, of a hollow shaft for supporting a drying cylinder to permit the heating medium to enter the cylinder, a pipe of less diameter than the shaft and passing through the shaft, a cap secured to said box and having a threaded opening, a hollow bolt surrounding a portion of the pipe for supporting the same, and means operated by the bolt for forcing the packing material between the shaft and the box.

5. In a device of the kind described, the combination with a metal drying cylinder and a hollow bearing box, of a hollow shaft secured to the drying cylinder and mounted in said box, there being an annular space between the inner end of said shaft and said box for placing packing material of a compressible nature therein, a cap having screw threads on its inner end for closing the outer end of said box, the cap having a threaded opening extending axially through the same to receive an externally threaded elongated hollow bolt structure, a steam outlet pipe passing through the hollow shaft and hollow bolt, a ring located in the annular space in which the packing material is located, the ring being connected to a hub through which the steam outlet pipe passes, arms for integrally connecting the ring and hub, the inner end of the said bolt engaging the outer end of the hub, a squared portion on the outer end of said bolt for the purpose of rotating the bolt for forcing the ring against the packing material, a stuffing box on the outer end of the hollow bolt, all constructed and arranged as and for the purpose described.

CHARLES HENRY ATKINS.
